95,432

DESIGN FOR A FOOD SLICER

John Reece Jones, Atlanta, Ga.

Application February 7, 1935, Serial No. 55,298

Term of patent 14 years

To all whom it may concern:

Be it known that I, John Reece Jones, a citizen of the United States, residing at Atlanta, in the county of Fulton and State of Georgia, have invented a new, original, and ornamental Design for a Food Slicer, of which the following is a specification, reference being had to the accompanying drawing, forming part thereof.

Figure 1 is a front elevation showing my new design.

Figure 2 is an elevation of one side thereof.

Figure 3 is a top plan view.

Figure 4 is an elevation of the other side.

I claim:—

The ornamental design for a food slicer, as shown.

JOHN REECE JONES.
